(57) **CLAIM**

The ornamental design for a rear combination lamp for an automobile, as shown and described.

DESCRIPTION

FIG. 1: a front view of a rear combination lamp for an automobile;

FIG. 2: a plan view of the rear combination lamp for an automobile;

FIG. 3: a left side view of the rear combination lamp for an automobile; and,

FIG. 4: a front perspective view of the rear combination lamp for an automobile as seen from the left side.

The broken lines in the drawings illustrate portions of the rear combination lamp for an automobile that forms no part of the claimed design.
